UNITED STATES PATENT OFFICE.

WILLIAM S. WELLS, OF SOUTH BETHLEHEM, PENNSYLVANIA, ASSIGNOR TO BENJAMIN EASTWOOD COMPANY, OF PATERSON, NEW JERSEY, A CORPORATION OF NEW JERSEY.

WARPING MACHINE.

1,409,129.

Specification of Letters Patent. Patented Mar. 7, 1922.

Application filed January 9, 1919. Serial No. 270,350.

To all whom it may concern:

Be it known that I, WILLIAM S. WELLS, a citizen of the United States, residing at South Bethlehem, in the county of Lehigh 5 and State of Pennsylvania, have invented certain new and useful Improvements in Warping Machines, of which the following is a specification.

Warping machines of a well-known type 10 are provided with a going friction member, usually belt-and-pulley driven, which is shiftable by means of a foot treadle and suitable connections into and out of driving contact with a rigid concentric driving band 15 or tread on the reel, the reel rotating when the contact is established, as by pressing on the treadle, and coming to a stop when it ceases. Whenever an "end" breaks and the warper has to rotate the reel backward to 20 find the broken end he has at present to do this by hand, the contact between friction wheel and driving band on the reel being of course then disestablished, and as he must also employ his hands in winding the warp 25 paid off by the reel temporarily on his arm in a loose skein or bundle the operation is extremely tedious and slow and it is a very difficult matter to find the broken end with celerity.

My principal object by this invention is to 30 provide means shiftable toward and from the reel and including, with a suitable support, a rotary driven member journaled therein and movable therewith into and out 35 of driving engagement with the reel, a going driving member also journaled in said support, and reversible reversing gearing connecting said members, whereby having properly set the mechanism for that purpose the 40 reel may be power-rotated backward as well as forward, thus leaving the attendant full freedom for winding up the warp on his arm and watching for the defect in the warp when rotating the reel backward.

In the drawings,

Figure 1 is a side elevation of the improved warping machine;

Figure 2 is a plan view, partly in section, of the principal parts of the invention;

Figure 3 is a section on line 3—3, Figure 2;

Figure 4 is a plan, partly in section, of the reversible reversing gearing;

Figure 5 is a sectional view of the going driving member; and

Figure 6 is a plan, partly in section, of a part of the driven member.

The reel *a* is journaled in the frame *b*. *c* is a suitably driven pulley and *d* a belt driven thereby. *e* is a treadle fulcrumed in the frame and extending as usual across the machine parallel with the axis of the reel and in convenient reach of the operator's foot. *f* is a forked bracket or support fulcrumed in the frame parallel with the reel axis and having journaled therein, also parallel with said axis, a shaft *g* having fixed to its inner end a friction wheel *h* adapted to bear against the rigid tread or band *a'* on the reel, to drive the same, and having fixed to its outer end, by the set screw *i*, a dished, outwardly concave gear *j* peripherally toothed at the inside. The shaft *g*, friction wheel *h* and gear *j* together constitute the driven member hereinbefore mentioned; longitudinal movement thereof is prevented by the bearing portion *f''* of bracket *f*, which gear and friction wheel abut.

On the shaft *g* is freely rotative a sleeve *k* which is aligned with and abuts the hub gear *j*, the sleeve being held against movement longitudinally of the shaft by gear *j* and bearing portions *f'* of the bracket or support *f*. The sleeve has a feather *l* extending from its outer end partway toward its inner end, and at its inner end it has two diametric arms *m* on which are journaled transmission pinions *n* which are housed in and mesh with the internal teeth of the gear *j*, the sleeve and its arms forming a carrier for the pinions. On the sleeve *k* and splined thereto (by having a groove receiving the feather *l*) is a collar *p* having teeth or lugs *p', p''*, one on each side thereof, the lug *p'* being adapted to engage in a notch *q* in the arm *f'* of the support *f*. The sleeve, with its arms and pinions, and the collar together form the reversible reversing gearing hereinbefore mentioned.

Journaled on sleeve *k* is a pulley *r* whose periphery receives the belt *d* and which has an inward annular flange *s* so that the pulley forms a guard around the gear *j*; the open side of said gear bears against the face of the pulley within the flange so that gear and pulley become a housing for grease or lubri-

cant, which may be introduced at the plugged opening *t* in the gear. Pulley *r* has an inwardly projecting toothed hub or pinion *u* which meshes with the pinions *n*, and it also has an outwardly projecting hub *v* formed with an internal shoulder *w* to abut the end of feather *l* and with a notch *x* to receive the lug *p''* of collar *p*. The pulley is confined by the feather and gear *j* against movement longitudinally of the shaft *g*. Pulley *r* forms the aforementioned going driving member.

With pulley *r* in rotation (being turned in the direction of the arrow in Figures 1 by belt *d*), it will be apparent that when the collar *p* is by its lug *p''* interlocked with the pulley *r* the sleeve *k* becomes fast with relation to said pulley (because the collar is splined to the sleeve), in consequence of which the pinions *n*, held against rotation on their own axes, carry the driven member *g*, *h*, *j* around with the pulley, so that if the support be now shifted to bring the friction wheel *h* against the reel band *a'* the reel will be rotated in the direction of the arrow adjoining it in Figure 1, or forward; and that when the collar *p* is by its lug *p'* interlocked with arm *f'* of support *f* the sleeve will be held against rotation, in consequence of which the rotating pulley will through the pinions *n*, now rotating on their own axes, rotate the member *g*, *h*, *j* contrary to the direction of rotation first stated if the friction wheel be shifted into contact with the reel band *a'* and so turn the reel contrary to the arrow in Figure 1, or backward. When the reel is rotated backward it moves at slower speed than when driven forward, as will be obvious.

40 The shifting of the clutch-device formed by the collar so as to reverse the direction of rotation of the reel is preferably accomplished by a device arranged parallel with the treadle and extending across the machine so as to be in convenient reach of the operator, and herein shown as consisting of a rod *y* arranged to slide longitudinally in suitable brackets *z*, one end of said rod being engaged with a lever *2* having a stud 45 engaged in a peripheral groove in the collar and fulcrumed in support *f*. A spring 50 connects the lever with a point on support *f* in dead-center alinement, relatively to the lever, with its fulcrum, so that the 55 spring normally tends to hold the collar at either limit to which it is shifted.

The shifting of the support *f* so as to bring the friction wheel *h* into driving contact with the reel to drive the latter forward or backward, according as the clutch device has been set one way or the other, is accomplished by pressure of the foot on treadle *e* through the medium of a pitman 60 connecting the latter with the support *f*, 65 gravity (and, it may be, a spring *6* also)

retracting the support to clear the friction wheel from the reel when the pressure is removed.

Having thus fully described my invention, what I claim as new and desire to secure by Letters Patent is:

1. The combination, with supporting means including a frame and a support shiftable therein, of a rotary element to be driven journaled in the frame and toward 75 and from which said support is shiftable, means to drive said element including a rotary driven member journaled in said support and shiftable therewith into and out of driving engagement with said element, a going driving member journaled in and shiftable with said support, and reversible reversing gearing arranged in and shiftable with said support and connecting said members. 85

2. The combination, with supporting means including a frame and a support shiftable therein, of a rotary element to be driven journaled in the frame, a reversible gearing means for driving said element including a 90 rotary driven member journaled in said support and shiftable therewith into and out of driving engagement with said element, means, including a treadle extending substantially parallel with the axis of said element, for shifting said support, and means, having an operating part extending substantially parallel with the treadle, for reversing said gearing means. 95

3. In combination, with the frame and 100 a rotary element to be driven journaled in said frame, means to drive said element including a support shiftable toward and from the same, a rotary driven member journaled in the support and movable therewith into 105 and out of driving engagement with said element, a going driving member journaled in said support, and reversible reversing gearing connecting said members, means, including a treadle extending parallel with the 110 axis of said element, for shifting said support, and means, having an operating part extending and movable parallel with the treadle, for reversing said gearing. 115

4. In combination, a support, a rotary 115 driven member, a rotary driving member, and a rotary carrier all arranged on a common axis in said support, said driving and driven members having concentric toothed portions, a pinion journaled in said carrier 120 and meshing with both of said toothed portions, and a clutch device splined on and shiftable longitudinally of the axis of the carrier, said clutch device having means when shifted in one direction to lock it 125 with the support against rotation and when shifted in the other direction to lock it with the driving member against rotation relatively thereto.

5. In combination, a support, a rotary 130

driven member journaled in the support, a carrier having an axial sleeve and journaled on the driven member, a driving member journaled on the sleeve, the driving and driven members having concentric toothed portions, a pinion journaled on the carrier and meshing with both of said toothed portions, and a clutch device splined on and

shiftable longitudinally of the sleeve, said clutch device having means when shifted in one direction to lock it with the support against rotation and when shifted in the other direction to lock it with the driving member against rotation relatively thereto.

In testimony whereof I affix my signature. 15
WILLIAM S. WELLS.
